CONTROL SYSTEM

Application filed March 24, 1928. Serial No. 264,435.

This invention relates to motor control systems and more particularly to the control of direct current motors.

The object of the invention, generally stated, is to provide, in a motor accelerating system, for effecting the actuation of a plurality of switches in a predetermined sequence to progressively short circuit sections of a starting resistor.

10 A more specific object of the invention is to provide for effecting the progressive operation of a series of accelerating switches independently of the current conditions prevailing in the motor.

15 It is a further object of the invention to provide for protecting the motor from excessive currents when the motor, after having been running in one direction, is reversed, causing it to operate in the other direction.

20 Other objects of the invention will become apparent when the following description is considered in connection with the accompanying drawing, wherein the single figure is a diagram illustrating the circuit connections of the motor control system.

25 Referring to the drawing, a motor 1 is shown that comprises an armature 2 and a shunt field winding 3. A manually operable switch S is arranged to connect the control scheme to the source of supply designated by the reference characters P and N. A manually operable master control switch C is used for controlling the directional contactors 4 and 5, whereby the direction of operation of the motor may be determined.

30 To establish the operating circuit for the motor, the line switch S is closed and the master control switch C is moved either to the "F" position or the "R" position. Assuming that switch S is closed and the master control switch C is moved to the "F" or forward position, a motor circuit is thus established from the conductor P through contact members 6 of the reversing contactor 4, the armature 2 of motor 1, contact members 7, conductor 8, the coils 9 and 11 of the current limit relays 10 and 12, and resistor sections 13 to 16, inclusive, of the starting resistor 17 to the conductor N. Closure of the line

45 switch S also establishes a circuit for the

shunt field 3 as is readily apparent from an inspection of the drawing.

The contact members 6 and 7 are obviously in circuit closing position because the closure of the master control switch C to the "F" position, caused the operation of the directional contactor 4 through the energization of the actuating coil 18 of the directional contactor 4. Obviously, if the switch C is moved to the "R" position, the actuating coil 19 of the directional contactor 5 is energized and the contact members 20 and 21 are closed, thus establishing a motor circuit for reverse operation.

50 As shown, the resistor 17 in this particular application of the invention is divided into four sections 13, 14, 15 and 16. In order to provide for shunting these sections, a plugging relay 22 and accelerating relays 23, 24 and 25 are provided. The purpose of resistor section 16 is to provide sufficient resistance in the motor circuit, in excess of that required for starting the motor from rest, to prevent excessive currents in the armature circuit when the motor is "plugged", that is, when the voltage applied to the armature is reversed while the armature of the motor is rotating.

55 The contactor 22 normally operates when the motor is started from rest as its actuating coil 26 is connected in a circuit extending from line conductor P through one portion of switch S, the contact members of one of the reverse current relays 10 or 12, the actuating coil 26 and through a second portion of switch S to the conductor N. The current limit relays 10 and 12 are biased to a circuit closing position by the adjustable spring members 27 and 28 but are held against closing, when the directional contactors 4 and 5 are deenergized or open, by the arm-like projections 29 and 30 disposed to engage the armatures of the current limit relays 12 and 10, respectively.

60 The coil windings 9 and 11 are so mounted on the relays that their respective magnetic effects oppose the biasing effect of the spring members 27 and 28, and the number of winding turns is so chosen that the contact members 31 and 32 will be in open circuit position when an excessive motor current passes

through the coils 9 and 11. The biasing force of the springs, acting in the direction shown and being made adjustable by the adjustable stops 33 and 34, may be great enough to retain the contact members 31 and 32 closed against the pull of the coils 9 and 11 when these coils are energized by a normal full load armature current or the normal current drawing by the armature during starting. However, it is desirable that the relays 10 and 12 be actuated to their respective open-circuit positions before the current in the motor reaches a value of current which would be drawn by the motor when it is "plugged". Therefore, when the motor is "plugged", the relays will not close until the current in the motor has fallen to a safe value, which will be the value at which the relay biasing springs 27 and 28 overcome the effect of the actuating coils 9 and 11. The value of current, above which the coils 9 and 11 will hold the contact members 31 and 32 open, may be varied by using adjustable springs or springs of different strengths. The current limit relays 10 and 12 are constructed and adjusted to close contact members 31 and 32 with the respective operations of the reversing contactors 4 and 5, when the motor is started from rest, and are prevented from closing when the motor is "plugged" until the motor current has fallen to a safe value.

It will, therefore, be readily understood that when the motor is "plugged", the plugging contactor 22 will be held open and the entire resistor 17 maintained in the armature circuit of the motor until the current has fallen sufficiently to allow one of the current limit relays 10 or 12 to close, depending on which directional contactor has closed, and energize the actuating coil 26 of the contactor 22 which, when closed or energized, shunts the plugging resistor section 16 at the contact members 35.

The accelerating relays 23, 24 and 25, which are employed for shunting the resistor sections 15, 14 and 13, respectively, are provided with actuating coils 36, 37 and 38. The actuating coils of these relays are energized by a circuit extending from line conductor P through the contact members of one of the current limit relays 10 or 12, the coils 36, 37 and 38, which are connected in parallel circuit relation with each other, through the contact members 39, 40 and 41 of the time limit relays 42, 43 and 44, respectively, to the line conductor N. Consequently, the contact members 39, 40 and 41 must be closed, i. e., time-limit relays 42, 43 and 44 must be energized before the corresponding accelerating contact members 45, 46 and 47 can be actuated to circuit closing position.

In order to control the operation of the time-limit relays 42, 43 and 44, a reactor 48 comprising an inductor coil 49 having a comparatively large number of turns wound on a

core 50, and capable of storing up a substantial amount of magnetic energy is utilized. By connecting the actuating coils 52, 53 and 54 in a local closed series circuit including the inductor or reactor, they will remain energized for a period of time after the energizing circuit has been interrupted, the current being supplied by the collapsing magnetic field of the inductor coil 49. The circuit for the relay-actuating coils 52, 53 and 54 extends from line conductor P, through the inductor coil 49, the relay actuating coils 52, 53 and 54, contact members 55 of contactor 51 or contact members 56 of the plugging relay 22, to line conductor N.

The local closed series or discharge circuit for the relay-actuating coils and the inductor coil 49, which becomes active, when the contact members 55 and contact members 56 are opened, to maintain the current flowing in the circuit, comprises the actuating coils 52, 53, 54, inductor coil 49, and a variable resistor 57, all of which are connected in a closed series circuit with reference to the line conductors P and N. The variable resistor 57 is connected, in shunt or parallel-circuit relation, to the inductor coil 49 and the coils 52, 53 and 54. Consequently, when the energizing circuit for the relay-actuating coils is interrupted by the opening of contact members 55 and 56, current will be maintained in the relay coils until the energy of the collapsing magnetic field of the inductor coil 49 has decreased to a predetermined value.

The relays 42, 43 and 44 are normally biased to circuit making position by means of adjustable spring members 58, 59 and 60. These several springs may be so adjusted that they will close the relays when different values of current prevail in the circuit. The same result may be accomplished by adjusting the magnetic pull of the several relay actuating coils by varying the number of turns in the windings of each coil, as shown. Because of these respective adjusting means, the time-limit relays may be made to operate in a definite sequence, and since their operation completes the energizing circuits for the actuating coils of the accelerating contactors 23, 24 and 25, respectively, the sections 15, 14 and 13 of resistor 17 may be shunted in any desired order; and the motor brought up to speed.

In this application, after the closure of the contact members 47 of the accelerating contactor 25, its actuating coil 38 is maintained energized by a bridging member 61 which is disposed on the armature of the contactor as illustrated and completes a circuit in parallel relation to the resistor 17.

The auxiliary contactor 51, which, when not energized, provides one circuit for energizing the coil 49 of the reactor 48 and for energizing the coils 52, 53 and 54, may have its actuating coil 62 connected across the en-

tire resistor 17 and be energized to open the contact members 55 with the first inrush of current to the motor. Since the contact members 56 of the plugging relay 22 will open when the voltage is first applied to the motor, the energizing circuit for the coil 49 is, therefore, interrupted when voltage is applied to the motor for starting.

When the contact members 56 of the plugging relay 22 and the contact members 55 of the auxiliary contactor 51 are opened, the actuating coils 52, 53 and 54 of the time-limit relays are energized by current caused by the collapsing magnetic field of the inductor coil 49, thus preventing the accelerating contactors 23, 24 and 25 from operating to shunt sections of the resistor 17. The accelerating contactors will operate in sequence, however, as the current in the loop or local series circuit including the reactor coil 49 decreases, thus shunting the sections of the resistor 17 in sequence and causing the motor to come up to speed.

When all the contact members 35, 45, 46 and 47 have closed and the resistor 17 is shunted, the actuating coil 62 of the auxiliary contactor is deenergized, permitting the contact members 55 to close. With the contactor 51 deenergized, the actuating coils of the time-limit relays 42, 43 and 44 will be reenergized to thereby cause the relays to be actuated to their circuit-interrupting positions. When, at this stage, the time-limit relays are in their circuit-interrupting positions, the actuating coils 36 and 37 are deenergized, thereby causing said switches to "drop out", that is, open the contact members 45 and 46. The shunt circuit for the starting resistor is not affected by these functions, since one of the current limit relays, 10 or 12, still has its contact members closed. In consequence, the plugging relay 22 is still energized and the accelerating relay 25 is energized by reason of the holding circuit through the contact member 61.

The auxiliary contactor 51 is now in a position to effect another operation of the accelerating relays or contactors when the motor is "plugged". However, as the operating coil 38 of the accelerating contactor 25 is maintained energized by the bridging or contact member 61, the resistor 17 will be maintained shunted until the circuit through the coils 9 and 11 of the current limit relays is interrupted by disconnecting the motor to stop or reverse the same.

In the system illustrated, the actuating coils of the directional contactors 4 and 5 are connected in circuits extending from the line P through one or the other of the contacts of the master control switch C, depending on the direction in which the master switch is moved, one or the other of the actuating coils 18 or 19 to the conductor N, as illustrated.

When the line switch S is in the "off" posi-

tion, the contact members 55 of the auxiliary contactor 51 and the contact members 56 of the plugging relay are closed. They also return to that position when the directional contactors 4 and 5 are deenergized. Accordingly, when the line switch S is closed, a circuit is provided through the reactor coil 49 and the actuating coils 52, 53 and 54 of the time-limit relays 42, 43 and 44. The motor will start to rotate when either contact members 6 and 7 or contact members 20 and 21 are caused to close as a result of the operation of the master controller C.

When the motor starts from rest, the current through the actuating coils 9 and 11 of the current limit relays 10 and 12 will be insufficient to hold the contact members 31 and 32 open. Accordingly, a circuit is established through one or the other of these contact members, depending upon the direction of operation of the motor, for the actuating coil 26 of the plugging relay 22. The contact members 35 are, therefore, closed to shunt the resistor section 16. At the same time, the circuit through contact members 56 is interrupted, thereby disconnecting the reactor coil 49 and the time-limit relay actuating coils 52, 53 and 54 from the source of supply. This alone, however, does not interrupt the circuit through the relay windings, since the contact members 55 of the auxiliary contactor 51 are disposed in the circuit. But with the first flow of current through the motor, voltage is impressed across the starting resistor 17, thus energizing the actuating coil 62 of the auxiliary contactor 51 and thus causing the contact members 55 to open. With the above described operation of the auxiliary contactor 51, the reactor coil 49 and the coils of the accelerating relays 23, 24 and 25 are disconnected from the source of supply.

Immediately upon the disconnecting of the reactor coil 49 from the source, the magnetic energy which is stored therein caused current to flow through the loop or closed series circuit, including the variable resistor 57, and the actuating coils of the time-element relays 42, 43 and 44, causing them to hold their contacts in circuit-opening positions for a predetermined period. However, as the current gradually decreases, the relays will close in a predetermined order, depending upon the adjustments of the relays.

The period of time delay which is effected by the time-limit relays may be varied considerably by adjusting the resistor 57 in the loop circuit.

In the system illustrated, the time-limit relay 42 will operate first, causing the contactor 23 to operate to shunt resistor section 15, then contactors 43 and 44 will operate in order, causing the contactors 24 and 25 to shunt respective resistor sections 14 and 13. When the accelerating contactor 25 operates the

contact member 61 on this contactor establishes a holding circuit for the actuating coil 38, whereby the contact members 47 will be held closed to maintain the resistor 17 shunted. Since the resistor 17 is shunted by the contact members 47, the actuating coil 62 of the auxiliary contactor 57 will be deenergized. Upon the closing of switch 55, the reactor coil 49 and the time-limit relay-actuating coils 52, 53 and 54 are again connected to the source of supply in order that conditions will be in readiness for the next starting of the motor.

When the motor is running at full speed 15 in one direction and the motor is "plugged", by reversing the voltage impressed on the motor, the current limit relays 10 and 12, as described before, will function to hold all the relays open, that is, deenergized until the 20 current in the motor circuit falls to such a value that one or the other of the biasing springs 27 or 28 of the current limit relays will effect the closure of one or the other of the contact members 31 or 32.

25 Responsive to the closing of the contact members of the current limit relays 10 or 12, the plugging relay 22 will shunt resistor section 16 and while this is happening, the contact members 55 of the contactor 51 are opened, but the circuit to the reactor coil 49 and the coils 52, 53 and 54 of the time-limit relays are maintained energized until the contact members 56 are opened, that is, until one or the other of the contact members 31 30 or 32 of the current-limit relays 10 and 12 are closed. Upon the opening of the contact members 55, the time-limit relays will function in the manner described heretofore.

40 Since the inductor coil 49 is provided with the core member 50 made of magnetic material, the magnetic energy that may be stored in the inductor coil may be of a relatively high value, thereby effecting a long time delay in operation of the relays.

45 While I have described my invention in the preferred form, it will be readily understood that many modifications may be made thereof without departing from the scope of the invention, as defined in the appended claims.

I claim as my invention:

1. In a control system, in combination, a plurality of switches, a separate relay for controlling the operation of each switch, a coil winding for each relay, an inductor connected to said coil windings, a circuit for energizing said inductor and said coil windings, means disposed in shunt to said inductor and coil windings to provide a discharge circuit for said inductor, and means for disconnecting the inductor and said coil windings from said energizing circuit, thereby permitting the energy stored in the inductor to be dissipated through the relay actuating coils.

60 2. In a control system, in combination, a

series of relays, a coil for actuating each relay, an inductor and a resistor connected in loop circuit relation to said relay actuating coils, a source of electrical energy, means for connecting and disconnecting said inductor to said source for storing energy in the inductor, and means for adjusting the relays to respond to different values of current flowing through their actuating coils to effect their operation in sequence, when the inductor is disconnected from the source of energy.

3. In a control system, in combination, a source of energy, an electric motor, a resistor in circuit relation therewith, a plurality of accelerating switches for short circuiting sections of the resistor, a plurality of relays for controlling the operation of the accelerating switches, an actuating coil for each relay and means for adjusting each relay to respond to different values of current in the actuating coils, an inductor connected in loop circuit relation with said actuating coils, means normally connecting said actuating coils and inductor to said source, said means disposed to automatically interrupt said connection when the motor is initially energized, permitting the inductor to be discharged to energize the relay coils for predetermined periods and to maintain the relays in their open positions, said means subsequently re-establishing the connection of said coils and the inductor after the relays have effected operation of the accelerating switches, and, means associated with one accelerating switch for holding itself closed to short circuit the resistor, after it has once closed.

4. In a control system, in combination, a source of energy, an electric motor, a resistor in series circuit relation therewith, a plurality of accelerating switches for short circuiting the resistor, a plurality of relays for controlling the operation of the accelerating switches, an actuating coil for each relay and means rendering said relays responsive to different current values flowing in the relay actuating coils, an inductor and a variable resistor for effecting a time delay in the de-energization of the relays, said inductor being connected in loop circuit relation with the relay actuating coils and the variable resistor, means for connecting the inductor and said relay coils to the source of energy, said means being automatically responsive to disconnect the inductor and said relay actuating coils from the source of energy with the first in-rush of current to the motor.

5. In a control system, in combination, a source of energy, an electric motor, a starting resistor in series circuit relation therewith, a plurality of accelerating switches for short circuiting the starting resistor, a plurality of relays for controlling the operation of the accelerating switches, an inductor for providing a time delay in the deenergization of the relays, a variable resistor for varying the pe-

65 period of delay, an actuating coil for each relay, the actuating coils being connected in loop circuit relation with the inductor and the variable resistor, means normally connecting the inductor and the relay actuating coils to the source of energy, and means responsive to the energization of the motor for disconnecting the relay actuating coils from said source and allowing current from the inductor to energize the coils and the variable resistor, and means in the relays making them responsive to the different current values in the loop circuit to effect the actuation of the accelerating contactors in sequence as the current in the loop circuit decreases.

6. In a control system, in combination, a source of energy, a reversible electric motor, a starting resistor in series circuit relation therewith, a plurality of accelerating switches for short circuiting said starting resistor, a plurality of relays for controlling the operation of the accelerating switches, an inductor for providing a time delay in the operation of the relays, actuating coils for the relays, a variable resistor for varying the speed of operation of the relays, a loop circuit including means for determining the current conditions in the relay actuating coils at which the relays will be responsive to operate, a circuit for connecting the inductor across the source of energy when the motor is first energized and means operative upon the energization of the motor for disconnecting the inductor from the source of energy, allowing it to discharge its electrical energy through the actuating coils of the relays and the variable resistor, to control the closure of the relays, maintaining them in their open circuit position until the current in the loop circuit has fallen to a predetermined value, a plugging switch for short circuiting a section of the resistor and means for holding said plugging switch open until the current in the motor circuit has reached a predetermined value, said means preventing the interruption of the circuit through the inductor until said plugging switch has closed.

7. In a control system, in combination, a source of energy, a reversible electric motor, a starting resistor in series circuit relation therewith, a plurality of accelerating switches for short circuiting sections of the starting resistor, a plurality of relays for controlling the operation of the accelerating switches, an inductor for effecting a time delay in the operation of the relays, a variable resistor for varying the period of delay in the operation of the relays, a plurality of actuating windings for said relays, a loop circuit comprising the inductor, the relay actuating windings, and the variable resistor, a plurality of means normally connecting the inductor, and the relay windings to the source of energy, said means being responsive to the

current flowing in the motor circuit for disconnecting said windings from the source of energy when the motor is energized, allowing the inductor to discharge magnetic energy through the relay actuating windings to effect the closing of the accelerating switches, means associated with one of the accelerating switches and effective upon the closure thereof for holding it closed to short circuit the starting resistor, and means for delaying the interruption of the means connecting the inductor and relay to the source of energy when the motor is being plugged until the current in the motor circuit has reached a predetermined condition.

8. In a control system, in combination, a source of energy, an electric motor, a starting resistor, a plurality of switches for short circuiting sections of the resistor in progressive sequence, a plurality of relays for controlling the operation of said switches, a plurality of actuating coils for effecting the operation of said relays, an inductor and a variable resistor disposed to provide a time delay in the operation of the relays, a circuit for said relay actuating coils comprising the inductor, the variable resistor, and said actuating coils, connected in loop circuit relation, means for energizing the inductor and the relay actuating coils when a voltage is applied to the motor, and means disconnecting said energizing means, allowing the current produced by the inductor to maintain the relay actuating coils energized for a predetermined time to effect a time delay in the operation of the resistor short circuiting switches.

9. In a control system, in combination, a plurality of relays, an actuating coil for each relay, an inductor capable of storing magnetic energy for providing a time delay in the operation of the relays, said inductor being disposed in circuit relation with said relay coils, a resistor connected in a circuit including said resistor, said inductor and the relay actuating coils, means for energizing the inductor, and means for adjusting each relay to respond to a different current of a predetermined value flowing in said inductor.

10. In a control system, in combination, a series of relays, a coil for actuating each relay, an inductor connected in series relation to the actuating coils of said relays, a resistor connected in shunt relation to said actuating coils and inductor for regulating the discharge current of the inductor through said relay coils, means for energizing said inductor, and means for adjusting the relays to respond to different current values passing through their actuating coils.

11. In a motor-control system, in combination, a motor having a starting resistor connected in circuit relation therewith, a source of power for energizing the motor, a plurality of switches for shunting sections of the

- starting resistor, a plurality of relays for effecting the actuation of said switches, an actuating coil for each relay, an inductor, means connecting said inductor in loop-circuit relation to said relay-actuating coils, electroresponsive means for normally connecting said actuating coils and inductor across the source of power when the motor is initially energized, said inductor being disposed to effect 5 a gradual increase of current in said relay-actuating coils, means for adjusting the relays to respond to different values of current in their actuating coils to effect the closure of the resistor-shunting switches in progressive sequence. 10
12. In a motor-control system, in combination, an electric motor having a resistor connected in circuit relation, a switch for short circuiting said resistor, a relay that is normally biased to its closed position and having a coil for effecting the operation of said relay to its open position, a source of energy for the system, an inductor connected in loop-circuit relation with the actuating coil 20 of said relay, means for normally connecting said source to the inductor, and means automatically disconnecting said inductor from said source when the motor is energized and for permitting the electrical energy stored 25 therein to be dissipated through said relay-actuating coil, whereby said relay may be held open until a predetermined current condition prevails in the loop circuit. 30
13. In a motor-control system, in combination, an electric motor having a resistor connected in series-circuit relation therewith, a switch for short circuiting said resistor, a normally closed relay for effecting the operation of said switch, an actuating coil for 35 said relay, an inductor connected in loop-circuit relation with said relay-actuating coil for providing a time delay in the operation of the relay when the motor is being started, means for energizing the inductor 40 to thereby cause said relay to be actuated to its open position when the motor is energized, means for automatically disconnecting the inductor from the source, means connected in circuit relation to said inductor 45 and actuating coil and disposed to cause said inductor to dissipate its magnetic energy in the actuating coil of the relay when the inductor is disconnected from said source, and means for adjusting the relay so that it will 50 close to effect the operation of the resistor-short-circuiting switch when a predetermined condition prevails in the loop circuit. 55
14. In a control system, in combination, a source of energy, an electric motor, a resistor 60 in series-circuit relation therewith, a plurality of accelerating switches disposed to short circuit sections of the resistor, a relay for controlling the operation of each accelerating switch, an actuating coil for each relay, and means disposed to effect sequential 65
- operation of said accelerating switches comprising an inductor connected in loop-circuit relation with the relay-actuating coils, means for connecting said inductor and said relay coils across said source, means for automatically disconnecting them, when the motor is connected to said source, to cause said relays to again close to effect sequential operation of the accelerating switches, and means disposed to re-energize said relay coils and inductor when the motor has been fully accelerated. 70
15. In a control system, in combination, a source of energy, a reversible electric motor and a starting resistor in series relation therewith, a plurality of switches for short circuiting sections of the starting resistor, means responsive to the current conditions in the motor for closing one of said switches, said means being disposed to hold the switch open for a predetermined period after the motor is plugged, a plurality of relays each provided with actuating coils for controlling the operation of the other resistor-short-circuiting switches, and means for gradually increasing the current in said coils for effecting operation of said relays in progressive succession independently of the current conditions in the motor, said means comprising said actuating coils, an inductor coil and a 80 variable resistor connected in loop-circuit relation, means for connecting said inductor coil and said relay-actuating coil in series-circuit relation across the source of energy when said motor is connected to said source 85 of energy, means for disconnecting said loop circuit from the source of energy when the motor is first started, and means for preventing operation of said disconnecting means when the motor is plugged until predetermined current condition prevails in the motor. 90
